UNITED STATES PATENT OFFICE.

GEORGE A. CLUFF, OF PATERSON, NEW JERSEY, ASSIGNOR OF TWO-FIFTHS
TO JOHN J. POWERS, OF PATERSON, NEW JERSEY.

MEANS FOR STOPPING LOOMS AT INTERVALS.

SPECIFICATION forming part of Letters Patent No. 704,436, dated July 8, 1902.

Application filed December 3, 1901. Serial No. 84,508. (No model.)

To all whom it may concern:

Be it known that I, GEORGE A. CLUFF, a citizen of the United States, and a resident of Paterson, in the county of Passaic and State 5 of New Jersey, have invented a new and Improved Means for Stopping Looms at Intervals, of which the following is a full, clear, and exact description.

The purpose of this invention is to provide 10 a mechanism for automatically stopping the movement of a ribbon or other loom when a certain length of goods has been woven. In the manufacture of ribbons it is the custom to weave the ribbon in lengths of ten yards; 15 and the special object of this invention is to stop the ribbon-loom accurately at every ten yards along the length of the ribbon, after which the ribbon may be moved slightly with the warp-threads and the weaving then resumed, the result of which operation is that 20 the ribbon will have a small part at each ten yards in which there is no filling, this part serving as a mark for subsequently cutting the ribbon into the ten-yards length referred 25 to above.

This specification is a specific description of one form of the invention, while the claims are definitions of the actual scope thereof.

Reference is to be had to the accompanying 30 drawings, forming a part of this specification, in which similar characters of reference indicate corresponding parts in all the views.

Figure 1 is a side view of the invention showing it applied to a ribbon-loom. Fig. 2 35 is a front elevation of the same. Fig. 3 is a detail sectional view of the cloth-beam and sand-roll. Fig. 4 is an enlarged side view of the trip device. Fig. 5 is a section on the line 5 5 of Fig. 4. Fig. 6 is a plan view of 40 the clock. Fig. 7 is a section on the line 7 7 of Fig. 6; and Fig. 8 is a view showing a length 45 of the ribbon with the filling or weft threads omitted at one point, so as to mark the ribbon at every ten-yards or other length desired.

a represents the sand-roll of the loom, *a'* a gear in connection therewith, and *a²* the cloth-beam. With the gear *a'* is meshed a gear *b* on a worm-shaft *b'*. The worm-shaft *b'* is 50 mounted to turn in the frame *c* of the clock *c'*, such frame being held in place by a bracket

c². (See Figs. 1 and 2.) The clock *c'* is of the usual construction—namely, it is in the form of a disk with worm-teeth on this disk meshing with the shaft *b'*. 55

c³ indicates the stationary pointer or hand of the clock. As the finished ribbon or other product of the loom is wound up the clock *c'* is driven in time with the sand-roll and by the proper adjustment of the parts the clock 60 may be made to show precisely the number of yards passing around the sand-roll and wound on the cloth-beam. Reference to Fig. 6 will show that in the form here illustrated the clock is intended to perform one revolution for every ten yards wound on the cloth-beam. 65

The clock-disk turns in direction of the arrow, (see Fig. 6,) and on the face of the disk is a crown-cam *d*. This cam is so located on 70 the disk *c'* that when ten yards are indicated thereby the cam runs under a lever *d'*, fastened to the clock-frame *c* by a clamp *d²*. (See Fig. 6.) The lever *d'* is connected by a cord *d³* to the counterweighted carrier *e* of 75 the hook *f*. This carrier *e* is fulcrumed on a suitable frame-piece *e'*, fastened to the framing of the loom. *g* indicates a pivoted stop, which is normally engaged with the tailpiece *e²* of the carrier *e* to hold the carrier raised, 80 as in Fig. 1. The stop *g* is held in this position by the pressure of the weighted carrier thereon, and the instant the lever *d'* moves down under the action of the cam *d* the carrier *e* is lifted, lowering the tailpiece *e²* thereof. 85 This disengages the stop *g*, which then falls by gravity to the position shown in Fig. 4. Upon relaxation of the pressure on the lever *d'* the carrier falls by gravity from the position shown in Fig. 1 to the position shown 90 in Fig. 4.

e³ represents a stop on the frame *e'* which limits the releasing movement of the stop *g*.

h indicates the batten of the loom, and *h'* indicates an eye which is fastened to the 95 batten.

When the carrier *e* is raised to the normal or inactive position shown in Fig. 1, the bill of the hook *f* is out of the path of the eye *h'*; but when the carrier falls to the active position shown in Fig. 4 the bill of the hook is lowered into the path of the eye *h'*, and as 100

the eye moves forward it engages the hook and draws the same longitudinally backward as the batten returns. The hook is mounted to slide longitudinally in the carrier *e*, thus 5 allowing for the above-described movement. The hook *f* has a cord *f'* attached, such cord running around a pulley *f*² on the frame *e'* of the carrier *e*. This cord then passes over guide-pulleys *f*³, which may be arranged in 10 any suitable manner, and the cord is finally connected to the shipper *i* of the loom. *f*⁴ indicates a spring which holds the hook *f* normally in its forward position. (See Fig. 2.) The shipper *i* is connected with the mechanism for stopping and starting the loom, so 15 that when the hook *f* is drawn backward and strain is placed on the cord *f'* the shipper is moved to throw the loom out of action.

When the loom is started, the parts are 20 placed in the position shown in Fig. 1, and when ten yards of work or any other length desired are wound on the cloth-beam the cam *d* will automatically actuate the lever *d'* and throw the carrier *e*, so as to allow the stop *g* 25 to disengage itself. Then the carrier drops, so that the hook *f* is actuated to stop the loom. The operative of the loom may now perform such operations as are necessary to make the well-known mark in the ribbon, as illustrated 30 in Fig. 8, and then the operation of the loom is again started by throwing up the carrier *e* and disengaging the hook *f* from the staple or eye *h*'. The dog or stop *g* is then returned to its active position, and the parts again assume 35 the adjustment shown in Fig. 1.

The advantage of this invention is that it automatically stops the loom the instant that the desired quantity of ribbon or other fabric has been woven. It does not depend upon 40 the care of an operative in watching a device which merely indicates the number of yards woven. In the old apparatus as commonly employed the operative was called upon to watch the indicator and stop the loom 45 when the proper number of yards had been woven. In frequent instances the operator will allow the loom to go on past the necessary number of yards, and then the ribbon has to be unwound and measured.

50 Various changes in the form and details of my invention may be resorted to at will without departing from the spirit of my invention. Hence I consider myself entitled to all forms of the invention as may lie within the intent of my claims.

Having thus described my invention, I claim as new and desire to secure by Letters Patent—

1. In a loom attachment, the combination 60 with a part of the loom moving in a fixed path, of a device connected with the loom for throwing the loom out of gear, a carrier on which said device is mounted, and means operated periodically from the loom for moving said carrier.

65 2. In a loom attachment, the combination with a part of the loom moving in a fixed path

and provided with an eye, of a hook mounted to slide and connected with the loom to throw it out of gear, the hook being adapted to be 70 engaged by the said eye, means for normally holding the hook out of the path of the eye, and releasing means for the hook operated periodically from the loom, for the purpose specified.

75 3. In a loom attachment, the combination with a part of the loom, said part moving in a fixed path, of a hook connected with the loom to throw it out of gear, a carrier on which the hook is mounted to move into and out of 80 the path of the said part of the loom, means for normally holding the carrier with the hook in inactive position, and trip devices for said means, the trip devices being operated periodically from the loom, for the purpose speci- 85 fied.

4. In a loom attachment, the combination with a part of the loom, said part moving in a fixed path, of a hook connected with the loom to throw it out of gear, the hook being 90 adapted to be actuated by said part of the loom, means for normally holding the hook out of the path of the said part of the loom, and trip devices for said means, the trip devices being operated periodically from the 95 loom, for the purpose specified.

5. In a loom attachment, the combination with a part of the loom, said part moving in a fixed path, of a carrier, a hook mounted thereon and connected with the loom to throw 100 it out of gear, a stop normally engaged with the carrier to hold it with the hook out of the path of said part of the loom, and devices for releasing the dog to move the hook into the path of said part of the loom, the said devices 105 being operated periodically from the lever.

6. In a loom attachment, the combination with the clock driven in time with the loom, of a cam attached to the clock, a lever actuated from the cam, a fulcrumed carrier connected with said lever, a device mounted on said carrier and connected with the loom to throw it out of gear, the said device being adapted to be moved into the path of a part of the loom and to be engaged thereby for 115 the purpose specified.

7. In a loom attachment, the combination with a clock driven in time with the loom, of a cam on the clock, a lever actuated from the cam, a carrier, a hook mounted on the 120 carrier and connected with the loom to throw it out of gear, the hook being adapted to be engaged by a part of the loom, moving in a fixed path, a stop for holding the carrier with the hook normally out of the path of the said 125 part of the loom, and a connection between the lever and the carrier, for the purpose specified.

8. In a loom attachment, the combination with the batten provided with an eye, of a 130 hook connected with the loom to throw the same out of gear, a fulcrumed support on which the hook is mounted to slide, and means operated periodically for moving said

support to carry the hook into the path of the eye, for the purpose specified.

9. In a loom attachment, the combination with the batten of the loom provided with an eye, a dial driven in time with the loom, and a stationary pointer for indicating on said dial, of a cam on the face of the dial, a lever actuated from the cam, a counterweighted fulcrumed carrier, a hook mounted to slide on the carrier, a cord passing over pulleys and connecting the hook with the shipper of the loom to throw the loom out of gear, the hook being adapted to be engaged by the eye on the batten, a pivoted stop for holding the carrier with the hook normally out of the path of the eye of the batten, and a cord connecting the lever and the carrier, for the purpose specified.
10. In a loom attachment, the combination with a part of the loom moving in a fixed path, of a hook connected with the loom to

throw it out of gear and mounted to move longitudinally and also to swing in a vertical plane, the said hook being adapted to be engaged and moved longitudinally in one direction by said part of the loom to throw the loom out of gear, a spring for holding the hook normally in the opposite direction, means for normally holding the hook raised and out of the path of said part of the loom, and a releasing device for said means operated periodically from the loom to permit the hook to swing into the path of said part of the loom, for the purpose specified.

In testimony whereof I have signed my name to this specification in the presence of two subscribing witnesses.
